(57) **CLAIM**

The ornamental design for a pan top, as shown and described.

DESCRIPTION

FIG. 1 is an isometric view of a pan top.

FIG. 2 is another isometric view of the pan top of FIG. 1.

FIG. 3 is a top plan view of the pan top of FIG. 1.

FIG. 4 is a bottom plan view of the pan top of FIG. 1.

FIG. 5 is a front elevation view of the pan top of FIG. 1.

FIG. 6 is a rear elevation view of the pan top of FIG. 1.

FIG. 7 is a left side elevation view of the pan top of FIG. 1.

FIG. 8 is a right side elevation view of the pan top of FIG. 1.

FIG. 9 is an isometric view of the pan top of FIG. 1 with a pan bottom; and,

FIG. 10 is an isometric view of the pan top of FIG. 1 with a pan bottom.

Portions of FIGS. 1 through 10 are shown in evenly spaced broken lines illustrating portions of the article that form no part of the claimed design, and phantom lines illustrating environmental subject matter including a pan bottom that form no part of the claimed design.

1 Claim, 8 Drawing Sheets
